UNITED STATES PATENT OFFICE.

CHARLES M. HICKEY, OF STOCKTON, CALIFORNIA.

TRACTION DITCHING-MACHINE.

1,184,238.

Specification of Letters Patent. Patented May 23, 1916.

Application filed December 26, 1914. Serial No. 878,997.

To all whom it may concern:

Be it known that I, CHARLES M. HICKEY, a citizen of the United States, residing at Stockton, in the county of San Joaquin, State of California, have invented certain new and useful Improvements in Traction Ditching-Machines; and I do declare the following to be a clear, full, and exact description of the same, such as will enable others skilled in the art to which it appertains to make and use the same, reference being had to the accompanying drawings, and to the characters of reference marked thereon, which form a part of this application.

This invention relates to improvements in ditching and excavating machines, the object of the invention being to produce a traction ditching machine advancing under its own power.

The particular aim and object of the invention is to produce such a machine as will dig the ditch to the desired depth and slope the sides thereof simultaneously and lift and carry the excavated dirt away as rapidly as possible.

A further object of the invention is to produce a machine, the structure and operation of which will tend to aid, rather than retard, the advance movement of the machine as the ditch is excavated and also to have the respective operations and operating structures therefor so positioned as to perfectly balance the machine so as to cause it to be most efficient operation while excising the least necessary amount of power.

The invention also embodies certain details with respect to the cutting of the ditch and clearing away of the dirt, all of which will appear hereinafter.

A still further object of the invention is to produce a simple and inexpensive device and yet one which will be exceedingly effective for the purposes for which it is designed.

These objects, I accomplish by means of such arrangement and relative position of the parts as will fully appear by a perusal of the following specification and claims.

On the drawings, similar characters of reference indicate corresponding parts in the several views.

Figure 1 is a side elevation of the device. Fig. 2 is a top plan view of the same. Fig. 3 is a fragmentary detailed view of the

bearings for the side cutter shafts and for the conveyer frame. Fig. 4 is a top plan view of a fragmentary portion of the bearings for the side cutter shafts and for the conveyer frame. Fig. 5 is a sectional view taken on a line X—X of Fig. 4. Fig. 6 is a sectional view taken on a line Y—Y of Fig. 3. Fig. 7 is a side elevation of a guiding pan. Fig. 8 is a top plan view of the same. Fig. 9 is a sectional view taken on a line Z—Z of Fig. 8.

Referring now more particularly to the characters of reference on the drawings, the numeral 1 designates the main frame of the device suitably constructed out of channel iron or other suitable material and supported on its forward end on wheels 2 and near its rear end on driving wheels 3 suitably mounted on a shaft or axle 4.

The numeral 5 designates the power which may be a gasoline motor or any other suitable or adaptable form of power, which, acting through the medium of transmission gears and other well known structures, is used to drive the wheels 3 and advance the dumper and is likewise used to operate the ditch cutting mechanism in a manner as will presently appear.

The ditch cutting mechanism is so positioned that that portion thereof which projects into and cuts the ditch is beyond the rear wheels of the device so that the weight and bulk of the tractor is carried ahead of the ditch so that there will be no danger of the same caving into the dirt adjacent the ditch. This ditch cutting mechanism embodies a driven shaft 6 on which is pivotally hinged a cutter chain supporting frame or ladder 7 which is constructed in any desired manner and of any suitable material.

The shaft 6 is driven through the medium of suitable geared transmission from the power 5 and secured on such shaft 6 are a plurality of tumblers 8 adapted to drive the cutter chains 9, such cutter chains at their lower end moving over suitable tumblers 10 similar in structure to the tumblers 8 and suitably secured to a shaft 11 journaled in the lower end of the frame 7.

The cutter chains 9 are disposed in pairs so that one, two or three units may be operated according to the width of the ditch desired to be dug. On each pair of such chains 9 are a plurality of cutter buckets 12 and between each pair of such cutter buckets are disposed

cutter bars or scarifiers 13. With the movement of the cutter chains 9 these scarifiers or cutter bars 13 move along in the dirt 14 of the ditch and loosen or scarify the same 5 so that the succeeding cutter bucket will readily cut into such dirt and carry it out of the ditch.

As the buckets and cutter bars 13 leave the ditch and move up above the ground 10 level 15, they move into a guiding pan consisting of two channel shaped parts 16 and 16^a telescoping into each other in a manner as shown at 17. This telescoping effect allows of this pan 16—16^a being always positioned directly at the ground level so that as the buckets move out of the ditch they will move through such pan and thus not lose any of the dirt which they are carrying. The lower end of the pan 16—16^a is 15 provided with a scraper 18 projecting along the ground level and adapted to engage any slight irregularities in the ground and level the same, so that the bottom end of the pan will always be immediately adjacent the top 20 edge of the ditch along its entire width.

The dirt which is carried up through the pan 16—16^a is discharged from the buckets 12 into a chute 19 which delivers it to a longitudinal conveyer 20, which in turn delivers it to two transverse conveyers 21 which carry the dirt to each side of the machine. The conveyers 20 and 21 are of course suitably operated by geared transmissions from the power 5 provided with 25 suitable clutches or other mechanical devices, etc., for operating the same.

The cutter chain frame 7 may be raised or lowered in any suitable manner, but I have provided as an illustration a cable 22 operated 40 by a drum 23 suitably connected by gears and clutches with the power 5. The cable 22 projects over a pulley 24 and is provided with a hook 25 which may be engaged with the lower end of the frame 7 in any 45 suitable manner and then with the operation of the drum 23, the frame 7 and all its connected parts may be raised on its pivotal point 6 according as different depths of ditches are desired to be dug or in a similar 50 manner the entire mechanism may be raised until above the ground level when it is desired to transfer the machine from one point to another.

A pair of bracing and supporting rods 55 26 are secured to the frame 1 and project down to the shaft 11 where they are suitably bolted to sleeves 27 into which project the ends of such shaft 11. To prevent the said braces 26 from pulling loose from the ends 60 of the said shaft 11, the interior of each sleeve 27 is provided with a shoulder 28, there being washers 29 abutting against such shoulders 28, such washers 29 being secured to the ends of the shafts 11 to hold the 65 sleeves 27 in position on such ends of the

shaft 11. The braces 26, at their upper ends, are provided with a plurality of holes 30, whereby they may be bolted in different positions on the frame 1 according as the frame 7 may be raised or lowered for different 70 depths of ditches.

The above structure and operation is such as accomplishes the digging of a straight vertical ditch, but in order to make the proper kind of a ditch for all purposes, it 75 is necessary for the sides to be made sloping to prevent caving. I therefore provide the following structure for this purpose, namely: Secured to the frame 1 on each side of the rear end thereof, is a pair of projecting supporting bars 31. The numeral 32 designates a shaft journaled in each pair of arms 31 at the outer ends thereof, such shafts 32 being also journaled on the frame 1. These shafts 32 are to be driven through 80 suitable transmission means from the power 5 and each carries on its outer end a beveled gear 33.

The numeral 34 designates a cutter shaft disposed obliquely on each side of the cutter frame 7 and clamped onto said cutter shafts 34 are cutting knives 35 disposed in alternate relation with respect to each other. Said shafts 34, at their upper ends, are journaled in bearings 36 connected with the 90 bars 31 and each shaft is provided with a beveled gear 37 meshing with its corresponding gear 33. At their other ends, the shafts 34 fit into guide bearings 38 in such a manner that normally they do not strike the bottom of said bearings, thus allowing for a slight movement therein to compensate for the strain due to vibration of the parts. The said bearings 38 are held by arms 39 pivotally connected with lips 40, as at 41, such lips 40 being connected with the member 7. The members 39 are provided with bolts 42 movable through curved slots 43 in the lips 40 to allow of the position of the bearings 39 being changed when the angle of the shafts 95 34 is changed to make a greater or less slope to the side of the ditch. When this change is to be made, the rods 31 are moved either 100 inwardly or outwardly and set at different positions, this being allowed of by reason 105 of such rods being provided with a plurality of holes 31^a for receiving the bolts which connect the rods 31 to the frame 1. When these rods 31 are moved in the manner specified, the shafts 32 slip through the bearings 110 32^a on the frame 1 and the gears 37 would then be replaced by gears of a different pitch in order to conform to the change thus made.

From the foregoing description it can be 115 seen that I have provided a traction ditching machine wherein the weight and bulk of the tractor is carried ahead of the ditch so that there will be no danger of the same caving in the dirt adjacent the ditch. I 120 130

have likewise provided an admirable way of digging ditches of different widths, depths and of providing sloping sides therefor, all of which features are essentially 5 vital in the construction of a successful ditching machine.

While I am aware that many ditching machines have been constructed and patented, still I believe that the above enumerated 10 features are novel and have utility in a marked degree.

While I have, on the drawings accompanying this specification, set forth in detail a connected system of gears, chains, clutches 15 and other transmission means for various parts of the mechanism, still in practice, a great many varied constructions for this purpose may be allowed, hence, I have not herein described the same in detail but have 20 merely referred to the same sufficiently to define the same in connection with those features upon which I claim invention.

Having thus described my invention what

I claim as new and useful and desire to secure by Letters Patent is:— 25

A ditching machine of the character described comprising a supporting frame, a cutter frame mounted on said supporting frame and carrying a cutting means, a telescopic pan mounted on said supporting 30 frame and projecting below the same, a scraper on the lower member of said pan arranged to move in advance of the ditch and level the ground surface whereby the lower end of the pan will maintain a position adjacent the top edge of the ditch to form a close joint between the pan and ground surface adjacent the ditch, said cutting means being movable over said pan, as 35 described.

In testimony whereof I affix my signature in presence of two witnesses.

CHARLES M. HICKEY.
